UNITED STATES PATENT OFFICE.

AUGUSTUS D. CURTIS, OF CHICAGO, ILLINOIS.

DESIGN FOR AN ELECTRIC-LIGHT REFLECTOR.

No. 38,854.

Specification for Design

Patented Oct. 8, 1907.

Application filed June 22, 1906. Serial No. 322,976. Term of patent 7 years.

To all whom it may concern:

Be it known that I, AUGUSTUS D. CURTIS, a citizen of the United States, residing at Chicago, in the county of Cook and State of Illinois, have invented a new, original, and ornamental Design for Electric-Light Reflectors, reference being had to the accompanying drawing, forming a part thereof.

In the accompanying drawing, Figure 1 is a front elevational view of a reflector made

according to my design; Fig. 2 is an end view of said reflector.

I claim

The ornamental design for an electric light reflector as shown.

AUGUSTUS D. CURTIS.
